[57] CLAIM

The ornamental design for a percussion article, as
shown and described.

DESCRIPTION

FIG. 1 is a rear perspective view of a percussion article,
showing my new design;

FIG. 2 is a rear elevational view thereof;

FIG. 3 is a front elevational view thereof;

FIG. 4 is a top plan view thereof;

FIG. 5 is a bottom plan view thereof; and,

FIG. 6 is a right side elevational view, the left side being
a mirror image thereof.
